UNITED STATES PATENT OFFICE.

HENRY A. WITHERELL, OF ROCKFORD, ILLINOIS, ASSIGNOR TO THE ROCKFORD SILVER PLATE COMPANY, OF SAME PLACE.

CASTER.

SPECIFICATION forming part of Letters Patent No. 367,329, dated July 26, 1887.

Application filed November 6, 1885. Serial No. 182,005. (No model.)

To all whom it may concern:

Be it known that I, HENRY A. WITHERELL, a citizen of the United States, residing in the city of Rockford, in the county of Winnebago and State of Illinois, have invented a new and useful Improvement in Casters, of which the following is a specification.

This invention relates to casters known as the "table-caster," but more especially to the 10 caster-rim in which the caster-bottles are supported, and to the swivel-support of the caster-rim. Its object is to produce a better article of its class at a less cost.

It consists in an independent swivel-support to the bottle-supporting caster-rim and in 15 the bottle-supporting rim.

In the accompanying drawings, Figure 1 is 20 an isometrical representation of a caster embodying my invention. Fig. 2 is a central vertical section. Fig. 3 is an isometrical representation of the swivel-support to the bottle-supporting rim, and Fig. 4 is an under face view of the bottle-supporting rim and its swivel-support.

The foot or pedestal portion A is of bell form, and its shaft B is produced in journal form and provided with an axial screw-bolt, C, rising therefrom, and, in connection with the handle D, fitted to receive the screw-bolt C to connect the parts, are in every essential feature 30 substantially identical with like parts of casters now in use and to be found in the trade.

The caster-rim E is produced preferably from plate material substantially uniform in 35 thickness and of proper dimensions, punched, pressed, spun, struck up or otherwise produced to the required pattern, fitted to receive

the caster-bottles, and to be properly supported on the pedestal.

A spider-formed support to the caster-rim 40 is produced with a tubular hub, F, to receive the journal portion of the pedestal in a manner to permit of an oscillatory or rotary movement thereon. The tubular hub F is provided with radial arms H in spider form, of 45 proper dimensions and in position to receive the central portion of the under face of the caster-rim, and extend outward between the holes prepared therein for the reception of the caster-bottles. The tubular hub of the 50 spider is placed on the journal portion of the pedestal. The caster-rim is then placed on the spider, and the handle put in place on the axial screw-bolt serves to fix the parts in place, and with the parts suitably finished completes 55 the caster.

I claim as my invention—

In a caster, the combination, with a base, a handle, a suitable connection between the base and handle, and a bottle-holder provided with 60 flanges depending from the rims of the bottle-openings in the holder, of a spider-support to the bottle-holder, the said spider being provided with arms constructed to rest between the flanges of two adjacent bottle-openings, 65 and curved to conform to the flanges around the openings, whereby the holder is locked to the spider as to motion in a horizontal plane and vertically removable therefrom, substantially as set forth.

HENRY A. WITHERELL.
